(57) **CLAIM**

The ornamental design for a spray bottle, as shown and described.

DESCRIPTION

FIG. 1 is a front perspective view of a first embodiment of a spray bottle, showing our new design; FIG. 2 is a front elevation view thereof; FIG. 3 is a right side elevation view thereof, with the left side elevation view being a mirror image of FIG. 3; FIG. 4 is a rear elevation view thereof; FIG. 5 is a bottom plan view thereof; FIG. 6 is a top plan view thereof; FIG. 7 is a front perspective view of a second embodiment of a spray bottle, showing our new design; FIG. 8 is a front elevation view thereof; FIG. 9 is a right side elevation view thereof, with the left side elevation view being a mirror image of FIG. 9; FIG. 10 is a rear elevation view thereof; FIG. 11 is a bottom plan view thereof; FIG. 12 is a top plan view thereof; FIG. 13 is a front perspective view of a third embodiment of a spray bottle, showing our new design, wherein the crossed-line hatching depicts a fabric material; FIG. 14 is a front elevation view thereof; FIG. 15 is a right side elevation view thereof, with the left side elevation view being a mirror image of FIG. 15; FIG. 16 is a rear elevation view thereof; FIG. 17 is a bottom plan view thereof; and, FIG. 18 is a top plan view thereof.
